WORKING FLUID FOR COMPRESSION
REFRIGERATION SYSTEMS

Stanley V. Cook, Dayton, and Alfred E. Bishop,

Corporation, Dayton, Ohio, a corporation of
Delaware

No Drawing. Application September 21, 1946,
Serial No. 698,423

7 Claims. (Cl. 252—68)

1

This invention relates to chemistry and more particularly to a working fluid for use in refrigerating systems.

In refrigerating systems employing a halogenated hydrocarbon as the refrigerant, slight traces of corrosion and copper plating have been discovered. It is believed this corrosion is due to slight traces of such end products as water and hydrochloric acid probably formed by the slow break-down of the refrigerant at temperatures occurring on the high temperature side of the system. The presence of water, is also objectionable in that it may result in the formation of ice crystals on the cold or low pressure side of the system.

To overcome this latter objection it has been the custom to add to the lubricant and the refrigerant a small amount of an antifreeze such as methyl alcohol. It has been found, however, that the addition of such antifreeze increases the corrosive and copper plating action taking place within the system.

It is the object of our invention to provide a working fluid which includes in addition to the halogenated hydrocarbon refrigerant and lubricant either with or without the antifreeze, one or more organic oxides of the type in which the oxygen atom is directly linked to two non-adjacent carbon atoms.

As one specific example of our invention, we employ as a refrigerant difluorodichloro methane. As a lubricant, we employ mineral oil. The amount of refrigerant and the amount of the mineral oil varies with the particular refrigerating system in which the working fluid is to be used. For example, the amount of lubricant required will vary according to the amount of lubricant space provided in the compressor as well as to the efficiency of the separation of the lubricant from the refrigerant after compression and to the dependability and effectiveness of the return of the lubricant from the other parts of the system to the compressor. In general, the amount of lubricant will vary between one-fifth and an amount equal to the refrigerant by weight, depending upon the characteristics of the system wherein it is to be used. Where no alcohol is to be used in the system, we include propylene oxide 1,3 in the amount of 1/2% to 5% of the refrigerant.

2

Where alcohol is to be used, we prefer to use methyl alcohol. In this event, the alcohol may be in the proportion of nine times the amount of the propylene oxide 1,3 but a greater proportion of propylene oxide such as in the proportion of 2 to 3 may be used if desired. Where alcohol is used we prefer to limit the combined total of the propylene oxide and the alcohol to between 1/2% and 5% of the amount of the refrigerant in the system.

Instead of the particular fluorine refrigerant named above, tetrafluorodichloroethane, methyl, methylene or ethyl chloride, or one of the other refrigerants mentioned in the Midgeley et al. Re-issue Patent 19,265, may be used. The mineral oil should be as free from corrosive substances as possible and of the proper viscosity characteristics. Synthetic lubricants may be used in place of the mineral oil.

Instead of the propylene oxide 1,3, the inhibitor may be selected from other members of the same series, which includes butylene oxide 1,3, butylene oxide 1,4, pentylene oxide 1,3, pentylene oxide 1,4, pentylene oxide 1,5, pentylene oxide 2,4, hexylene oxide 1,3, hexylene oxide 1,4, hexylene 1,5, hexylene oxide 1,6, hexylene oxide 2,4, and hexylene oxide 2,5. It should be understood that other names are used for these same oxides such as propene, butene, pentene and hexene as well as propylethylene and butylethylene. This series may be broken down into two groups of compounds: (1) compounds in which the oxygen atom is linked to the end carbon atoms and (2) compounds in which the oxygen atom is linked to non-adjacent but not necessarily the end carbon atoms of the molecular structure.

These oxides may be used with various alcohols used as antifreezes in the refrigerating system, such as methyl alcohol, ethyl alcohol, normal propyl and isopropyl alcohol, normal butyl and isobutyl alcohol, tertiary butyl alcohol and benzyl alcohol. The lower alcohols appear to be more effective as antifreezes, but the higher alcohols appear to contribute less corrosion. However, in all cases it appears that by the use of one of the members of the oxide series above described, particularly the propylene oxide 1,3, corrosion is effectively retarded and prevented.

The working fluids above described inhibit the

corrosion and copper plating action within the refrigerating system. This may be due to the fact that the organic oxides above described act to stabilize the refrigerant.

While the form of embodiment of the invention as herein disclosed, constitutes a preferred form, it is to be understood that other forms might be adopted, as may come within the scope of the claims which follow.

What is claimed is as follows:

1. A working fluid for a compression refrigerating system consisting of as its major constituents a refrigerant halofluoro derivative of an aliphatic hydrocarbon as the refrigerant and mineral oil and as its minor constituent a mono-hydroxy alcohol having no more than 4 carbon atoms in the molecule and an organic oxide inhibitor of the type in which the oxygen atom is linked directly to two non-adjacent carbon atoms in a linked hydrocarbon chain of 3 to 6 carbon atoms, said inhibitor being in an amount not more than 5% of the refrigerant in the system.

2. A working fluid for a compression refrigerating system which consists of as its major constituents a refrigerant fluorochloro derivative of an aliphatic hydrocarbon and a mineral oil lubricant and has as a minor constituent propylene oxide 1,3 in an amount of not more than 5% of the refrigerant in the system.

3. A working fluid for a compression refrigerating system which consists of as its major constituents a refrigerant fluorochloro derivative of an aliphatic hydrocarbon and a mineral oil lubricant and has as a minor constituent propylene oxide 1,3 in an amount of not more than 5% of the refrigerant in the system and a mono-hydroxy alcohol having no more than 4 carbon atoms in the molecule.

4. A working fluid for a compression refrigerating system which consists of as its major constituents a halogenated aliphatic hydrocarbon refrigerant and a liquid mineral oil lubricant and has as a minor constituent no more than an amount equivalent to 5% of the refrigerant of a member selected from the group consisting of propylene oxide 1,3, butylene oxide 1,3, butylene oxide 1,4, pentylene oxide 1,3, pentylene oxide 1,4, pentylene oxide 2,4, pentylene oxide 1,5, hexylene oxide 1,3, hexylene oxide 1,4, hexylene oxide 1,5, hexylene oxide 2,4, hexylene oxide 2,5 and hexylene oxide 1,6, and a mono-hydroxy alcohol having no more than 4 carbon atoms in the molecule.

5. A working fluid for a compression refriger-

ating system which consists of as its major constituents a halogenated aliphatic hydrocarbon refrigerant and a liquid mineral oil lubricant and has as a minor constituent no more than an amount equivalent to 5% of the refrigerant of a member selected from the group consisting of propylene oxide 1,3, butylene oxide 1,3, butylene oxide 1,4, pentylene oxide 1,3, pentylene oxide 1,4, pentylene oxide 2,4, pentylene oxide 1,5, hexylene oxide 1,3, hexylene oxide 1,4, hexylene oxide 1,5, hexylene oxide 2,4, hexylene oxide 2,5 and hexylene oxide 1,6, and a mono-hydroxy alcohol having no more than 4 carbon atoms in the molecule.

6. A working fluid for a compression refrigerating system consisting of as its major constituents a halogenated hydrocarbon refrigerant and a liquid mineral oil lubricant, and as its minor constituent an organic oxide inhibitor of the type in which the oxygen atom is linked directly to two non-adjacent carbon atoms in a linked hydrocarbon chain of 3 to 6 carbon atoms, said inhibitor being in an amount not more than 5% of the refrigerant in the system.

7. A working fluid for a compression refrigerating machine consisting of as its major constituents a halogenated hydrocarbon refrigerant and a liquid mineral oil lubricant, and as its minor constituent a mono-hydroxy alcohol having no more than 4 carbon atoms in the molecule and an organic oxide inhibitor of the type in which the oxygen atom is linked directly to two non-adjacent carbon atoms in a linked hydrocarbon chain of 3 to 6 carbon atoms, said inhibitor being in an amount not more than 5% of the refrigerant in the system.
